UNITED STATES PATENT OFFICE

ANDREW BODOR, OF NEWARK, NEW JERSEY

PAPER BOTTLE

Application filed March 5, 1931. Serial No. 520,284.

This invention relates to receptacles composed of paper or similar material, with particular reference to milk bottles.

Glass bottles, such as are used for a like purpose, are objectionable because of their inherent fragility, excessive weight, and difficulty in thoroughly cleansing their interiors, an operation necessary to proper sanitation.

It is therefore an object of this invention to provide a paper bottle resistant to the penetration and absorption of liquids, strong and durable to enable handling, without damage and loss of contents, which are retained in a thoroughly sanitary condition, and are provided with a removable paper cap of usual type.

A further feature is in the provision of a paper milk bottle conforming to the customary symmetrical shape of a glass bottle, and so inexpensive that it may be discarded when emptied after use, its cost being less than the expense of collecting, cleaning and sterilizing milk bottles of glass construction.

These and other advantageous features, later becoming apparent, are accomplished by the novel design, construction and arrangement of parts, hereinafter described and illustrated in the accompanying drawing, forming a material part of this disclosure, and in which:

Figure 1 is a perspective view of a partially coiled blank from which the bottle is made.

Figure 2 is a perspective view of bottle showing its cylindrical lower portion and ruffled upper portion as conically formed by the first operation.

Figure 3 is a side elevational view of the bottle after the second, or seat forming and flanging operation, and corrugated bottom.

Figure 4 is an enlarged fragmentary sectional view of the upper portion of the same.

Figure 5 is a side elevational view of the completed bottle.

Figure 6 is a fragmentary sectional view of the neck and mouth, showing the cap, seat and bead, and drawn to an enlarged scale.

Figure 7 is a similar view showing the bottom construction.

Figure 8 is a fragmentary sectional view taken on line 8-8 of Fig. 3, drawn to an exaggerated scale.

Figure 9 is a fragmentary sectional view similar to Fig. 6, but with the cap omitted.

The entire wall of the bottle is made from a single oblong rectangular blank 10 of suitable sheet material, as heavily calendered paper, uncreased and presenting four straight unbroken edges.

The width of the blank is such as to produce a completed bottle, wholly without waste of material, and its length is preferably such as to be coiled to constitute two or more layers of a thin walled cylinder 11, its edges slightly overlapping and being firmly and neatly secured, both inside and outside, by an adhesive unaffected by liquids.

These cylinders, which are uniform in diameter, length and all other respects, are placed upon a mandrel, tapered for approximately half the length of the bottle, and there subjected to a rotating conical die provided with means in connection with the mandrel, to produce a series of evenly spaced, uniform plaits or ruffles 12 widest at their upper extremity and gradually blending, as at 13, into the cylindrical body 14.

The extra thicknesses of material at these plaits is condensed under heavy pressure to present an essentially smooth appearance, and it is to be noted that all of the plaits are folded uniformly in the same direction.

The next operation is to enlarge the mouth portion, that is the upper end, of the bottle by especially designed machinery, at the same time forming a flat cap receiving seat 15 having a raised marginal flange 16 of such height as to permit curling tightly inward upon itself to constitute a condensed bead 17 to seat upon and seal the cap 18.

The bead 17 is so positioned, relative to the seat 15, as to retain the plain flat circular cap 18 in the space 19 in a liquid tight manner until forcibly removed, when the contents of the bottle are required.

The bottom closure of the bottle may be formed in any approved manner, as by the

insertion of a disc 20 having a down reaching annular flange 21 closely fitted to the interior of the cylinder, their edges being in register, and prior to insertion an adhesive is applied to the exterior of the flange.

Thereafter a knurling operation is performed on the upper portion of the flange, adjacent to the disc, forcing the material outwardly, in the form of vertical corrugations 10 22 into the walls of the surrounding cylinder forming a leak proof, permanent joint, the knurling and beading operations being performed by the use of expandible tools which also hold the flanged bottom in position.

15 This joint is further secured by coiling the plural walls of the cylinder 14 inwardly to form an enclosing bead 23 interengaging the upturned edge of the flange 21.

20 The entire bottle may be further sealed by covering the interior and exterior with melted mineral wax, thus effectually sealing the bottle and its content against any possible infiltration of air or leakage of contents.

25 Due to the plurally layered walls of the bottle an efficient, essentially rigid structure is produced, and by reason of designing special machinery for its construction, in addition to its simplicity and freedom of waste, the bottles can be produced at a cost comparatively low.

30 Although the foregoing is descriptive of the preferred embodiment of the invention, it will be apparent that minor changes may be made in its construction, without the exercise of invention or conflicting with the scope 35 of the claim hereto appended.

Having thus described the invention, what is claimed as new and desired to secure by Letters Patent, is—

40 A paper bottle comprising a body having a main cylindrical portion and a neck continuous with one end of said portion, a bottom for the opposite end of said portion, a cap, a right angularly disposed flange extending 45 from the outer end of said neck and providing at its inner portion a seat for the outer margin of said cap, and an inwardly and downwardly turned resilient portion continuous with said flange and engaging said seat 50 and the outer edge of said cap, whereby, to provide a V-shaped annular pocket for the outer edge of said cap.

In testimony whereof I affix my signature.
ANDREW BODOR.
